UNITED STATES PATENT OFFICE.

JACOB G. EICHLTZ, OF IDA GROVE, IOWA.

HARNESS-MACHINE.

SPECIFICATION forming part of Letters Patent No. 630,335, dated August 8, 1899.

Application filed March 15, 1898. Serial No. 673,904. (No model.)

To all whom it may concern:

Be it known that I, JACOB G. EICHLTZ, a citizen of the United States, residing at Ida Grove, in the county of Ida and State of Iowa, 5 have invented a new and useful Harness-Machine, of which the following is a specification.

My invention relates to sewing-machines, and particularly to a harness-machine for 10 sewing and repairing harness and other articles of leather and equivalent heavy material, the object in view being to provide in connection with a harness vise or clamp improved means for reciprocating a needle trans- 15 versely of the jaws of said vise or clamp, together with means for feeding the needle in a direction parallel with the jaws in a step-by-step movement.

A further object of the invention is to provide simple and efficient means whereby the 20 length of the steps of the feeding movement of the needle may be varied to suit the different articles in connection with which the machine may be used and also to provide 25 means whereby the needle may be held to reciprocate in a direction perpendicular to the faces of the jaws of the vise or clamp or may be arranged to reciprocate obliquely with relation thereto.

30 A further object of the invention is to provide a simple and efficient construction of thread-tension and means for varying the point of release thereof.

Further objects and advantages of this 35 invention will appear in the following description, and the novel features thereof will be particularly pointed out in the appended claims.

In the drawings, Figure 1 is a perspective 40 view of a sewing mechanism constructed in accordance with my invention. Fig. 2 is a central vertical sectional view of the same. Fig. 3 is a plan view, partly broken away. Fig. 4 is a detail transverse section of the 45 head of the needle-bar. Fig. 5 is a detail view in perspective of the feed mechanism detached. Fig. 6 is a similar view of the tension device. Fig. 7 is a detail view in perspective of a portion of the apparatus, showing the position of the needle.

Similar numerals of reference indicate cor-

responding parts in all the figures of the drawings.

The sewing mechanism forming an essential feature of my invention is illustrated in 55 the drawings as mounted upon a harness vise or clamp having a fixed member 1, carrying a fixed jaw 2 and a movable jaw 3, pivoted, as at 4, to a forwardly-projecting bracket 5, carried by the fixed member 1, said bracket 60 being hollow to form a thread box or receptacle and consisting of a floor 6 and end plates 7, said movable jaw 3 being mounted between, and hence laterally braced by, the side walls 7 of the thread-box. Also the members 65 of the vise are connected by an adjusting-bolt 8, which may be fitted with any suitable means, such as a nut 9, for varying the position of the movable jaw 3 with relation to the other member of the vise to clamp an object, 70 such as parallel folds or layers 10 and 11 of leather or analogous material, between the faces of the jaws and with the upper edge of such object projecting beyond the contiguous edges of the jaws to provide for connecting the edges of the folds or layers by a row 75 of stitching and the auxiliary or shuttle thread which is engaged with the loop of the main or needle thread during the projection of the needle through the folds or layers of 80 material which are being united.

Extending rearwardly from the fixed member of the vise, which constitutes a supporting-frame, are arms 12, which are provided with transversely-aligned seats or bearings 14 85 for the reception of the extremities of a feed bar or rack 15, and mounted upon said feed bar or rack for movement parallel with the planes of the vise-jaws is a carriage or feed-block 16, having a transverse or horizontal 90 guide-opening 17, which snugly fits the feed-bar 15, and also having a vertical guide-opening 18, in which is fitted for axial movement the spindle or stem 19 of a needle-bar carrier 20, said needle-bar carrier being provided at 95 its upper end with a bowed yoke 21, having horizontally-aligned guide-openings 22 and 23 for the needle-bar 24, said needle-bar being mounted in the guide for reciprocation toward and from the planes of the vise-jaws. 100

Formed in the upper side of the carriage 16 is a seat consisting of a groove 25, intersect-

ing the guide 18 and adapted to receive a cross head or pin 26, carried by the spindle or stem 19, when the needle bar is disposed perpendicular to the planes of the vise-jaw faces; but by elevating the carrier 20 sufficiently to unseat said cross head or pin 26 said carrier may be turned to position the needle-bar obliquely with reference to the faces of the vise-jaws, for a purpose hereinafter explained.

Various means may be employed for reciprocating the needle-bar; but in the construction illustrated the means shown consist of an operating-lever 27, pivotally connected with the needle-bar, as shown at 28, and having its upper end connected with the yoke 21 by means of a link 29, whereby the pivotal point of connection of the lever with the needle-bar is adapted to travel accurately in the path of movement of the needle-bar during the operation of the mechanism.

The feed bar or rack 15 is provided with one or more series of rack-teeth, the bar illustrated in the drawings being provided on opposite sides with rack-teeth 30 and 31, the teeth of the former series being coarse, while those of the latter are fine, and carried by the carriage 16 in operative relation with one series of the rack-teeth is a yielding feed-pawl 32, preferably consisting of a looped spring 33, attached at one end to the carriage 16 and having its free arm disposed to engage the teeth of the rack and normally and yieldingly held in engagement therewith by the resilience of the loop. Said pawl or yielding arm 32 of the spring-loop is extended beyond its point of contact with the teeth of the rack to form a trip-arm 34, which is arranged in the path of the backward movement of a cam-face 35, located upon the needle-bar near its front end, said cam-face forming one side of an enlargement or head of the needle-bar. The abrupt surfaces of the teeth of the rack-bar face in the direction of feeding of the carriage, and hence when the needle-bar is drawn rearwardly sufficiently to cause the engagement of its cam-face with the trip-arm 34 said pawl is held by the abrupt face of the engaged rack-teeth from yielding, and hence the carriage is advanced in the desired or feeding direction, the backward movement of the needle-bar being limited (to prevent disengagement of the cam-face from the trip-arm) by any suitable means, such as the contact of the head or enlargement of the needle-bar with the front guide 22. To prevent excessive movement of the carriage and yieldingly hold the same after each advance movement, I employ a holding-pawl 36, extending through a cut-away portion 60 or channel 37 in the front wall of the guide 17, said holding-pawl constituting one arm of a looped spring 38, corresponding substantially, in construction with the spring 33. The holding-pawl indicates, by snapping into engagement with a succeeding tooth, when the carriage has been advanced one step, and hence the operator is notified by the holding-pawl

when a succeeding advance of the needle-bar may be inaugurated. The pawl 36 is also extended to form a releasing-arm 39, which is located above the upper side of the carriage and projects laterally in rear of the trip-arm 34, as clearly indicated in Fig. 5. By pressing forwardly upon said releasing-arm the holding-pawl may be advanced to release the rack-teeth, and the contact of said releasing-arm with the trip-arm 34 of the feed-pawl 32 will disengage the latter from the teeth, whereby the carriage may be moved manually to the desired position upon the rack-bar. The rack-bar is held with one of its series of teeth in operative relation with the feed-pawl by means of locking-keys, which in the construction illustrated consist of pins 40, arranged in the arms 12 and engaging transverse seats in the extremities of the rack-bar, and it will be understood that by removing these holding-pins the rack-bar may be turned in its bearings in said supporting-arms to arrange the desired series of rack-teeth in operative relation with the pawl to insure the desired length of step during the feeding movement.

The head of the needle-bar is provided with a needle-seat 41, in which is fitted a needle 42, and also an awl-seat 43, in which is fitted an awl 44, the awl being preferably shorter than the needle and spaced therefrom a distance which is divisible evenly by the interval between the teeth of either of said series 30 and 31 of the rack-bar. The coarse teeth 30 may be equal to the interval between the needle and awl. The holding-pawl serves to indicate to the operator during the use of the rack-teeth 31 when the backward or re-tracting movement of the needle-bar should cease in order to obtain the short step of the carriage desired in connection with fine or close work. Also the head of the needle-bar is provided with a thread-guide 45, through which extends the thread 46 to the eye of the needle 42, said needle-thread approaching the guide 45 through the guide-slot 47, formed in the fixed jaw 2 of the vise, and the reel-spool 48, from which said thread is supplied, being conveniently located in the thread-box 5 at the base of the movable or adjustable jaw 3 of said vise. In connection with this thread-guide 45 is a tension-spring 49, operating in a groove 50 in the side of the needle-bar-head to intersect said thread in the guide 45 and lock the thread normally against movement through said guide, said spring being preferably of looped construction, as shown. Also this tension-spring is provided with a rearwardly-extending trip-arm 51, deflected outwardly at its rear end and adapted during the rearward movement of the needle-bar for engagement with a trip 52, disposed in the path thereof, said trip being adjustable to vary its position forwardly and rearwardly with relation to the path of movement of the trip-arm, whereby the release of the thread is adapted to occur at different points in the

path of movement of the needle-bar. In the construction illustrated said trip is pivotally mounted, as at 53, upon the yoke 21 of the needle-bar carrier, and it is adapted to be engaged with either of a plurality of seats 54, located at different distances from the front end of the needle-bar, said trip being preferably of yielding material, whereby it is adapted to be held by its inherent resilience in the seat with which it is engaged, while allowing the manual displacement thereof from one seat in order to provide for its engagement with another when it is desired to vary the point of release of the thread.

In operation the article to be stitched is arranged between the vise-jaws, and the needle-bar is reciprocated by the operation of the lever to cause the needle to pass through said article and carry with it the needle-thread. The needle-bar is then slightly backed to provide for the engagement with the loop of the needle-thread by an auxiliary or shuttle thread 55, such engagement being accomplished manually and being clearly indicated in Fig. 7. The needle-bar is then fully retracted, and when the cam-face of its head comes in contact with the trip-arm of the feed-pawl the carriage is advanced through an interval corresponding with that between two contiguous teeth of the engaged rack. During the advance movement of the needle-bar the awl 44 passes through the material at an interval from the needle, and hence when the carriage has been advanced in the direction of feed preparatory for a second stitch the needle is brought opposite the puncture formed during the previous stroke by the awl, and hence the movement of the needle through the material is facilitated. During the backward stroke of the needle-bar the thread-tension remains in engagement with the needle-thread a sufficient length of time to draw the auxiliary or shuttle thread into the opening which has been vacated by the needle, and it is obvious that by varying the position of the trip the auxiliary or shuttle thread may be drawn a greater or less distance into the material which is being sewed to suit the thickness of the article.

When it is desired to vary the path of the needle-bar with relation to the planes of the vise-jaw faces, or, in other words, to stitch obliquely through an article held by the vise-jaws, it is necessary simply to elevate the needle-bar carrier sufficiently to disengage the cross-head or pin 26 from the seat 25 and turn the carrier spindle or stem in the guide 18. Tilting movement of the carrier with relation to the supporting-frame is prevented by the engagement of the lower end of said spindle or stem with a guiding-keeper 56, suitably supported by the stationary member 1 of the vise. Also in order to provide for interchanging and replacing the needle and awl I employ means for detachably securing the same in place, said means consisting of

tapered keys or fastening-pins 57, fitted in suitable seats intersecting the seats 41 and 43 and adapted when driven into place to bind frictionally against the needle and awl to prevent longitudinal displacement thereof.

In the operation of the mechanism the extension of the upper edge of the material above the jaws of the vise and the passage of the needle through this extended edge portion of the material, such as a harness-strap or the equivalent thereof, is liable, except when the material is particularly stiff or resistant, to bend the same, and thus interfere with the perpendicular traverse of the needle or the accurate penetration of the material perpendicular to the opposite surfaces thereof. Therefore I prefer to employ an auxiliary clamp 58, connected by a tension brace-rod 59 with the yoke 21, said brace-rod being pivotally connected to the yoke, as at 60, to adapt it to be swung upwardly to remove the auxiliary clamp from operative relation with the jaws of the vise. The clamp which I have illustrated in the drawings consists of a collar or shoulder 61, a threaded stem 62, which may be formed as a continuation of the brace-rod 59, and a nut 63, threaded upon said stem for adjustment toward and from the shoulder or collar 61, whereby the exposed or projecting upper edge of the material to be punctured by the needle may be arranged between the planes of the shoulder or collar 61 and the nut 63 and the latter adjusted to firmly clamp said edge, and thus hold the folds or layers of the object in contact, while the brace-rod prevents the bending or deflection of said edge by reason of the pressure of the needle and awl in passing therethrough. Also in practice I may, as shown in the drawings, form a yielding locking-arm 64, extending forwardly from the shoulder or collar 61 and having a straight bearing portion 65 to engage one side of the nut 63 and hold the latter against loosening or unscrewing after it has reached the desired adjustment. Preferably the holder-arm 65 is looped rearwardly from its point of attachment to the clamp to provide the necessary resilience even when the nut 63 is adjusted close to the plane of the shoulder or collar 61.

In practice various changes in the form, proportion, and the minor details of construction may be resorted to without departing from the spirit or sacrificing any of the advantages of this invention.

Having described my invention, what I claim is—

1. In a harness-machine, the combination of a vise, and means for varying the relative positions of the jaws thereof, one of the vise-jaws being provided parallel with its face with a guide-slot, of a carriage supported by one of the vise-jaws for movement parallel with the faces thereof, and a reciprocatory needle-bar and operating devices mounted upon the carriage, the said slot in one of the vise-jaws forming a guide for the thread in

its passage to the needle carried by the needle-bar, substantially as specified.

2. In a harness-machine, the combination of a vise having fixed and movable jaws, a thread-box located between and supported by the jaws, means for varying the relative positions of the jaws, a carriage supported by one of the vise-jaws for movement parallel with the vise-jaw faces, and a needle-bar and operating devices mounted upon said carriage, substantially as specified.

3. In a harness-machine, the combination of a vise having a fixed jaw, a forwardly-extending hollow bracket supported by the fixed jaw and having side and bottom walls, and a movable jaw pivotally mounted between the side walls of said bracket to form a thread-box, means for relatively adjusting the vise-jaws, a carriage supported by one of the vise-jaws for movement parallel with the vise-jaw faces, and a needle-bar and operating devices mounted upon said carriage, substantially as specified.

4. In a harness-machine, the combination with a supporting-frame, of a feed-bar having ratchet-teeth, a carriage mounted upon said feed-bar for movement parallel therewith, a feed-pawl on the carriage for engaging the teeth of the feed-bar, and provided with a trip-arm, a holding-pawl also supported by the carriage for engagement with the teeth of the feed-bar, and a needle-bar mounted for reciprocation and provided with a cam-face in the path of which said trip-arm is arranged, substantially as specified.

5. In a harness-machine, the combination with a supporting-frame, of a feed-bar having ratchet-teeth, a carriage mounted upon said feed-bar for movement parallel therewith, a feed-pawl on the carriage for engaging the teeth of the feed-bar, and provided with a trip-arm, a holding-pawl also mounted upon the carriage for engagement with the teeth of the feed-bar, and having a releasing-arm in the path of which said trip-arm is arranged, and a reciprocating needle-bar having a cam-face in the path of which said trip-arm is arranged, substantially as specified.

6. In a harness-machine, the combination with a supporting-frame, of a feed-bar having a plurality of feed-racks, a carriage mounted upon said feed-bar and provided with a feed-pawl for engagement with the teeth of one of said racks, said feed-bar being adjustable to arrange different feed-racks in operative relation with said pawl, means for securing the feed-bar at the desired adjustment, and a needle-bar reciprocably mounted upon the carriage and provided with means for actuating the feed-pawl, substantially as specified.

7. In a harness-machine, the combination with a supporting-frame, of a terminally-swiveled feed-bar provided with a plurality of feed-racks, securing-keys for locking said feed-bar at the desired adjustment, a carriage reciprocably mounted upon the feed-

bar and carrying a feed-pawl for engagement with one of the feed-racks thereof, and a reciprocating needle-bar mounted upon the carriage and provided with means for actuating said feed-pawl, substantially as specified.

8. In a harness-machine, the combination with a supporting-frame, of a feed-bar having ratchet-teeth, a carriage mounted upon the feed-bar and provided with a feed-pawl for engagement with said ratchet-teeth, a needle-bar carrier swiveled upon said carriage for swinging movement in a plane parallel with the feed-bar, to dispose the needle obliquely thereto, and a needle-bar mounted in said carrier and provided with means for actuating said feed-pawl, substantially as specified.

9. In a harness-machine, the combination with a feed-bar having ratchet-teeth, a carriage mounted upon said feed-bar and provided with a feed-pawl, a needle-bar carrier swiveled upon the carriage with its axis perpendicular to the feed-bar, a needle-bar reciprocably mounted upon the carrier, and provided with means for actuating the feed-pawl, and means for securing the carrier in an adjusted position with relation to the carriage, substantially as specified.

10. In a harness-machine, the combination with a feed-bar having ratchet-teeth, a carriage mounted upon said feed-bar and provided with a feed-pawl, a needle-bar carrier swiveled upon the carriage with its axis perpendicular to the feed-bar, a needle-bar reciprocably mounted upon the carrier, and provided with means for actuating the feed-pawl, a cross-head or pin carried by the carrier for engagement with a seat in the carriage, and means for securing the carrier in an adjusted position with relation to the carriage, substantially as specified.

11. In a harness-machine, the combination of a feed-bar having rack-teeth, a carriage mounted upon the feed-bar and provided with a feed-pawl for engagement with said rack-teeth, a needle-bar carrier having a spindle mounted in a guide in the carriage, a keeper arranged parallel with the feed-bar to receive said spindle at a point remote from the feed-bar, and a needle-bar mounted upon the carrier and provided with means for actuating said feed-pawl, substantially as specified.

12. In a harness-machine, the combination of a carriage and means for imparting a step-by-step feeding movement thereto, of a needle-bar carrier swiveled upon the carriage, a needle-bar reciprocably mounted in guides in said carrier, and an operating-lever connected with the needle-bar for operating the same, substantially as specified.

13. In a harness-machine, the combination of a carriage and means for imparting a step-by-step feeding movement thereto, of a needle-bar carrier swiveled upon the carriage, a needle-bar reciprocably mounted in guides in said carrier, and an operating-lever loosely connected at its extremity with the carrier

and pivotally connected at an intermediate point with said needle-bar, substantially as specified.

14. In a harness-machine, the combination of a carriage and means for imparting a step-by-step feeding movement thereto, of a needle-bar carrier swiveled upon the carriage, a needle-bar reciprocably mounted in guides in said carrier, an operating-lever pivotally connected at an intermediate point with said needle-bar, and a link connecting the extremity of said lever with the carrier, substantially as specified.

15. In a harness-machine, the combination with a carriage and feeding mechanism for imparting a step-by-step movement thereto, of a needle-bar carrier having a yoke terminally provided with aligned guides, and being extended at one end to form a spindle mounted in said carriage, a needle-bar reciprocably mounted in said guides, and an operating-lever pivotally connected with the needle-bar and loosely connected at its extremity with the yoke, substantially as specified.

16. In a harness-machine, the combination with a carriage and feeding mechanism for communicating step-by-step forward movement thereto, of a reciprocatory needle-bar having a thread-guide, a tension-spring for normally clamping the thread to prevent movement thereof through said thread-guide, and a movable trip, adapted for engagement with either of a plurality of seats, and arranged in the path of said tension-spring, for actuating the same to release the thread, substantially as specified.

17. In a harness-machine, the combination with a carriage and feeding mechanism for communicating a step-by-step forward movement thereto, of a reciprocatory needle-bar having a thread-guide, a tension-spring for normally clamping the thread to prevent movement thereof through said thread-guide, and a pivotal trip adapted for engagement at its free end with either of a plurality of seats, to actuate said tension-spring to release the thread, substantially as specified.

18. In a harness-machine, a carriage, step-by-step feed mechanism for said carriage, a reciprocatory needle-bar, a yoke swiveled upon the carriage and having the needle-bar mounted thereon, whereby the needle-bar may be arranged in a position which is oblique with relation to the path of the carriage, and a retaining device for securing the yoke in a fixed position with relation to the carriage, substantially as specified.

19. In a harness-machine, a traveler-carriage, step-by-step feeding mechanism for said carriage, a yoke swiveled in the carriage, a retaining-pin for normally connecting said yoke and carriage, a needle-bar mounted for reciprocation in the yoke, and a tension-spring on the needle-bar, substantially as specified.

20. In a harness-machine, the combination of a slotted vise-jaw, a needle-bar arranged for movement in a direction transverse to said slotted vise-jaw and carrying a needle, and means whereby thread may be fed through the slot of the vise-jaw, and through said needle-bar and needle, substantially as specified.

21. In a harness-machine, the combination of a vise having a slotted jaw, a thread-box carried by the vise, and a needle-bar mounted for movements respectively transverse to and parallel with the slot in the face of the jaw, thread being fed from the thread-box, through said slot in the vise-jaw to a needle carried by said needle-bar, substantially as specified.

22. In a harness-machine, the combination with a vise, of a carriage mounted for feeding movement parallel with the jaws of the vise, a needle-bar carrier vertically and rotatably adjustable in said carriage, means for holding said carrier against rotatable adjustment when at one limit of its vertical movement, a needle-bar slidably connected with the carrier, and means for reciprocating the needle-bar.

JACOB G. EICHLTZ.
